UNITED STATES PATENT OFFICE.

NELS H. NELSON, OF MINNEAPOLIS, MINNESOTA.

SHOE TREAD.

Application filed April 27, 1923. Serial No. 635,111.

My invention relates to improvements in shoe treads.

Broadly it is the object of my invention to provide a cushioned tread of this kind adapted particularly, though not exclusively for athletic shoes, said tread embodying integral sole and heel members, pneumatically cushioned to promote the comfort of the wearer.

A further object is to provide a hollow shoe tread of the present nature equipped with internal shape retaining reinforcing members, certain of said members forming suction cups at the bottom of the tread to prevent slipping.

Another object is to supply a tread of this kind designed for ready and permanent application to the ordinary shoe sole.

With the foregoing and other objects in view, which will appear in the following description, the invention resides in the novel combination and arrangement of parts and in the details of construction herein-after described and claimed.

In the drawings, Fig. 1 is a bottom view of a shoe tread embodying my invention; Fig. 2 is a sectional view of a tread taken as on the line 2-2 of Fig. 1, said tread being shown attached to a shoe which is shown partly in section and partly diagrammatically; Fig. 3 is a sectional view taken on the line 3-3 of Fig. 2; Fig. 4 is a sectional view taken on the line 4-4 of Fig. 1 and Fig. 5 is a similar view taken on the line 5-5 of Fig. 1.

Referring to the drawings, wherein similar reference characters have been used to indicate similar parts throughout the several views, it will be observed that my improved tread serves as an outsole and comprises a combined sole and heel structure designed for application to the slip-sole of a shoe. Figs. 2, 4 and 5 illustrate the tread sewed to the slip-sole 10 of a shoe 11. The tread includes a sole section A and a heel section B, said sections being integral. The structure is made up of a top piece 12, bottom pieces 13 and 14 of the sole and heel sections A and B, sides 15 of the former and sides 16 of the latter and a front or riser 17 of the heel section B. Strengthening webs α between the upper and lower pieces 12 and 13, at the shank of the tread, reach inward from the sides, but do not meet at their inner edges. This arrangement provides a duct α' which

brings the hollow sole and heel sections into communication with each other. An endless recess 18 cast in the sides of the structure provides a marginal flange 19 at the upper edge of the structure through which a seam 20 is passed in sewing the tread to a shoe sole. In both the sole and heel sections are a plurality of interspersed, inverted cup-like members 21. The crowns of these members 21 are integral with the top piece 12, while the margins of said members, near the rims 21^a thereof, are integral with the bottom pieces 13 and 14. In addition to reinforcing the tread structure, the cup-like members 21 supply non-slipping suction cavities, the rims 21^a of said members being readily conformable with slight irregularities in a supporting surface to enhance the gripping of the surface by suction. Said rims 21^a also supply non-slipping projectons, the action of which supplements the suction gripping action of the tread structure. To further reinforce the tread longitudinally, I supply longitudinal ribs 22 cast integrally with the top piece 12. The sole and heel sections A and B being in communication one with the other as shown in Figs. 2 and 3, it will be understood that a hollow unitary structure is comprised thereby. In the front or riser 17 of the heel section B, I insert an air valve 23 of conventional type to which an air pump may be removably attached for the purpose of inflating the tread and lending greater resiliency thereto.

Being preferably formed of a good grade of live rubber, the tread is relatively light in weight and firm under the foot of the wearer. The suction cup members 21, aside from their part in reinforcing the structure, operate effectively as non-slipping elements, not only upon a floor, but upon the ground, as well.

Changes in the specific form of my invention, as herein disclosed, may be made within the scope of what is claimed without departing from the spirit of my invention.

Having described my invention, what I claim as new and desire to protect by Letters Patent is:

1. In a tread for shoes, hollow resilient sole and heel sections integral and communicating with each other, inverted cup-like members joined at their crowns with the tops of said sections, and at their margins near the rims thereof with the bottoms of

- said sections, longitudinal ribs within the structure, said ribs and inverted cup-like members serving to reinforce the structure, and a valved passage for introducing air into one of said sections.
2. A tread for shoes comprising a hollow resilient structure having interspersed, inverted cup-like members joined at the crowns thereof with the top of the structure and at their margins near the rims thereof with the bottom of the structure, and a valved passage for introducing air to the interior of the structure.
3. A tread for shoes comprising a hollow resilient structure formed with upper and lower spaced walls, a plurality of interspersed inverted cup-like members joined at the crowns thereof with the upper wall and at their margins near the rims with the bottom wall, the walls of said cup-like members being spaced from one another intermediate said upper and lower walls to form suction grippers and structural reinforcements for said tread.
4. A tread for shoes comprising a hollow resilient structure formed with upper and lower spaced walls, a plurality of interspersed inverted cup-like members joined at the crowns thereof with the upper wall and at their margins inwardly from the rims thereof with the lower wall of the structure, the walls of said cup-like members being spaced from one another intermediate said upper and lower walls to form suction grippers and structural reinforcements for said tread, the margins of said cup-like members protruding outwardly beyond said lower wall to supplement the suctional gripping action of said members.
5. In a pneumatic tread for shoes, a hollow resilient tread section, suction cups interspersed within the hollow portion of said tread section and longitudinally extending ribs disposed within said tread and between said suction cups for reinforcing said tread longitudinally.
6. In a pneumatic tread for shoes, a hollow resilient tread section, suction cups interspersed within the hollow portion of said tread section and longitudinally extending ribs disposed within said tread and between said suction cups for reinforcing said tread longitudinally, said ribs being integral with the top of the structure and of a depth short of confining the movement of air from one part of said section to another.

In testimony whereof, I have signed my name to this specification.

NELS H. NELSON.
